(57) **CLAIM**

The ornamental design for a wiring closet ventilation unit, as shown and described.

DESCRIPTION

FIG. 1 is a front perspective view of a wiring closet ventilation unit;

FIG. 2 is a back perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken line showing of parts of the drawings is included for the purpose of illustrating use and environment and forms no part of the claimed design.
